(57) **CLAIM**

The ornamental design for a windshield with pillars and forward accent, as shown and described.

DESCRIPTION

FIG. 1 is a front perspective view of a windshield with pillars and forward accent according to the invention;

FIG. 2 is a front view thereof;

FIG. 3 is a rear view thereof;

FIG. 4 is a top plan view thereof;

FIG. 5 is a bottom view thereof;

FIG. 6 is a side view thereof; and,

FIG. 7 is a rear perspective view thereof.

The dotted lines represent the bounds of the claim which form no part of the claimed design. The dashed lines represent the environment in which the article resides and forms no part of the claimed design.

1 Claim, 7 Drawing Sheets
